WRENCH SET

Marvin Saxby, Princess Bay, N. Y., assignor to
 Bayes Manufacturing Co., Inc., New York, N. Y.,
 a corporation of New York

Application February 1, 1950, Serial No. 141,663

4 Claims. (Cl. 81—71)

1

This invention relates to wrenches, and more particularly to sets of wrenches in which each individual wrench may be employed as needed, while remaining part of the set.

An object of the invention is to provide a novel and improved form of wrench set, in which a plurality of individual wrenches are movably secured in a novel frame or housing, whereby any selected wrench may be employed without disengagement from the housing or frame.

Another object of the invention is to provide a novel wrench set in which there are a plurality of guide and securing members pivoted on a common pin or shaft, with individual wrenches engaging each of said guide and securing members so as to be movable in relation thereto, and so arranged that any selected wrench may be used without disengagement from its guide and securing member.

A further object of the invention is to provide a novel wrench set of the type described, in which the guide and securing members are eccentrically mounted on the common pin or shaft, allowing any selected guide and securing member and its wrench to be turned substantially out of axial alignment with the rest of the guide and securing members, for effective use thereof.

Still another object of the invention is to provide a novel and improved wrench set of the type described, in which the individual wrenches are of the hexagon type commonly known as "Allen" wrenches, for engagement in matching hexagonal sockets formed in the heads of screws or bolts.

Still a further object of the invention is to provide a novel and improved wrench set of the type described, which is simple in design, inexpensive to manufacture, and which is highly effective and convenient for its intended purpose.

Other objects and advantages of the invention will become apparent from the following description of a preferred embodiment thereof as illustrated in the accompanying drawings, and in which:

Fig. 1 is a front elevational view of the wrench set, the long shanks of the individual wrenches being disposed in mutually parallel alignment.

Fig. 2 is a top plan view of the wrench set shown in Fig. 1.

Fig. 3 is a side elevational view of the wrench set of Fig. 1, as seen from the right side thereof.

Fig. 4 is a sectional plan view taken on plane 4—4 of Fig. 1.

Fig. 5 is a front elevational view somewhat similar to that of Fig. 1, but showing the middle

2

one of the wrenches with its long shank extended to an upwardly extended position.

Fig. 6 is a right side elevation somewhat similar to that of Fig. 3, but showing how the upwardly extended wrench of Fig. 5 has now been turned through an angle of ninety degrees in a clockwise direction, also carrying with it, its individual guide and securing member.

Fig. 7 is a perspective view indicating how the wrench set may be grasped in the hand, with one of its wrenches extended outwardly for use.

Where wrenches are to be used, it is necessary to have a set of wrenches in graduated sizes, and when mingled with other tools in the mechanic's tool box, or tool drawer, it frequently happens that the very size of wrench needed has been mislaid, become separated from the rest of the set, or otherwise not available, and the resulting inconvenience may cause embarrassing delay.

The present invention provides a wrench set in which all the wrenches are mounted in a common holder, yet each is available for instant use as needed, without disengaging it from the set, merely by turning the desired wrench out of alignment with the others.

In order to understand clearly the nature of the invention and the best means for carrying it out, reference may now be had to the drawings, in which like numerals denote similar parts throughout the several views.

As shown, there are a number of individual wrenches, 10, 12, 14, 16 and 18, each having a long shank 20, and a short shank 22 forming an angle with the long shank, both shanks being thus integral and formed hexagonal in cross section, which is common to the "Allen" wrenches. The individual wrenches 10, 12, 14, 16 and 18 are thus similar to each other, but differ in their cross sectional size, as seen best in Fig. 4, and are also somewhat different in the length of their shanks.

Stop lugs 24 project outwardly from each of the long shanks 20 of the individual wrenches. Each of the individual wrenches has its long shank 20 penetrating loosely through a bore 28 formed through the individual guide and securing members or hubs 30, there being thus one such hub 30 for each of the individual wrenches. The shanks 20 of the wrenches are thus seen to be freely turnable in the bores 28 of the hubs 30, and at the same time freely slide axially therein, so that, as seen in Fig. 5, an individual wrench 14 may be elevated by sliding it through its guide bore 28, until its stop lug 24 comes into

contact with the hub 30, blocking further movement in that direction of the wrench shank.

As seen best in Figs. 2 and 4, it is preferable to displace the bores 28 in the hubs 30, away from the diametral lines of the hubs, and further it is seen that the larger diameter bores 28 come closer to the outer edges of the hubs than the smaller diameter bores 26. With all the hubs 30 brought into axial alignment as in Figs. 2 and 4, it is seen that there is a frame pin 32 which penetrates eccentric aligned bores 34 in the hubs 30. The outer ends of the pin 32 may be peened over to retain all the hubs 30 thereon, while yet permitting them to turn freely on the pin. Or, if desired, diameter of the bores 34 in the two outermost hubs 30 may be made a little smaller than that of the other hubs 30, and the pin 32 pressed thereon to retain the intermediate hubs therebetween. If this latter method is used, then it is seen that the two outermost hubs 30 will not be turnable on the pin 32.

Each wrench is thus individually swivelled, and movable independently of all the other wrenches, so that it is easily moved into any position to permit use at any angle. Fig. 6 shows how any individual wrench may be turned through a full circle of 360 degrees, as indicated by the broken line circle 36 in the direction of the arrows and vice versa. As shown best in Fig. 7, any wrench, such as wrench 14, may be turned out of alignment with the others, into extended position, so that its short shank 22 is ready for insertion into the socket formed in a nut or bolt for turning the same. From Fig. 7, it is seen that the balance of the wrenches, namely 10, 12, 14, 16, and 18, combine to form a fine grip or handle, the long shanks 20 of said wrenches being grasped by the three fingers 40, 42 and 44, while the upstanding long shank of the wrench 22 extends between the fingers 44 and 46. At the same time, the short shanks 22 of the wrenches 10, 12, 16 and 22 lie over and against the thumb 48 of the hand. It is obvious that the assembly is firmly gripped.

It is also seen that any one of the individual wrenches may take the position of the extended wrench 14 in Fig. 7, and the others will provide a firm grip for the hand. Since the wrenches are secured together, in movable relation to each other to the extent indicated, it is seen that the entire assembly is quite compact, and that it may be inserted into a carrying case, for carrying in the pocket, or disposed in the tool case in similar manner, in a simple envelope type carrying case having a flap secured in closed position by a snap fastener.

Although I have described my invention in specific terms, it will be understood that various changes may be made in size, shape, materials and arrangement without departing from the spirit and scope of the invention as claimed.

I claim:

1. A wrench set comprising a plurality of hub members, means securing said hub members together in assembled relation to each other, a plurality of wrenches, each of said wrenches engaging one of said plurality of hub members, and being individually movable in relation to said hub members without disengagement there-

from, whereby any selected wrench may be brought into extended position for performing operative work therewith, all said wrenches being polygonal in cross-sectional contour.

5 2. A wrench set comprising a plurality of hub members, means securing said hub members together in assembled relation to each other, a plurality of wrenches, each of said wrenches engaging one of said plurality of hub members, and being individually movable in relation to said hub members without disengagement therefrom, whereby any selected wrench may be brought into extended position for performing operative work therewith, each of said wrenches 10 being substantially L-shaped and of polygonal 15 cross-sectional contour, one shank of each of which penetrates slidably each of said plurality of hub members.

20 3. A wrench set comprising a plurality of hub members, means securing said hub members together in assembled relation to each other, a plurality of wrenches, each of said wrenches engaging one of said plurality of hub members, and being individually movable in relation to 25 said hub members without disengagement therefrom, whereby any selected wrench may be brought into extended position for performing operative work therewith, all of said wrenches 30 being substantially L-shaped, one leg of the 30 wrench being hexagonal in cross section for engaging a matching socket to be turned, and the other leg of said wrench penetrating slidably each of said hub members.

4. A wrench set comprising a plurality of hub 35 members, means securing said hub members together in assembled relation to each other, a plurality of wrenches, each of said wrenches engaging one of said plurality of hub members, and being individually movable in relation to said hub members without disengagement therefrom, whereby any selected wrench may be brought into extended position for performing operative work therewith, each of said hub members comprising a disc, said securing means comprising a 40 shaft penetrating eccentrically disposed bores formed through each of said discs, parallel to the axis thereof, and each of said wrenches comprising a hexagonal rod bent into substantial L-shape forming two legs, one of said legs penetrating slidably a chordal bore formed in each of said hub members, and the other of said legs forming the operative member of said wrench insertable in a socket for turning the same, and stop means carried by the legs penetrating said chordal bore, for limiting the outward extension motion thereof.
